EDGAR W. BREISCH, OF EDGEWOOD, PENNSYLVANIA, ASSIGNOR TO WESTINGHOUSE ELECTRIC & MANUFACTURING COMPANY, A CORPORATION OF PENNSYLVANIA

HOT-FILAMENT RECTIFIER

Application filed November 5, 1920, Serial No. 422,019. Renewed October 11, 1923.

This invention relates to hot-filament rectifiers and, in particular, to means for increasing the rating and the life of such rectifiers.

5 In the operation of a hot-filament-rectifier bulb, the current passes from the bulb anode to the filament and then, combining with the filament current, increases the temperature of the filament. As the filament temperature determines the rating of the bulb, any method which will allow a greater rectified current without an increased heating of the filament will increase the capacity of the bulb or give a longer life at the same rating.

10 15 My invention relates particularly to filamentary rectifiers of the type wherein the filament temperature tends to follow the wave form of the current traversing the filament. Where the filament of the rectifier is energized from a small auxiliary coil on an alternating current transformer, and the load current is in phase with the heating current, the load current passes from the anode to the filament and there combines with the filament 20 25 current to increase the temperature of the filament, particularly at the peak of the current wave.

The main object of my invention, therefore, is to provide means whereby the rectified current and the filament current may be so displaced in time-phase that, when the rectified current is maximum the filament current is minimum. This may be done by means of an internal reactance in the transformer, or 30 35 by a separate reactance, so adjusted as to give the proper phase angle.

The single figure of the drawing is a schematic diagram of connections, showing a preferred form of transformer.

40 45 50 The alternating-current supply is fed through leads 1 and 2 to the primary coils 3, 3 of a transformer 4. The secondary coils 5, 5 are connected together and a midpoint 6 of such connection is connected to the negative terminal of the battery 7'. The coils 5, 5 have their outer terminals 7 and 8 connected respectively, to the anodes 9 and 10 of the bulbs 11 and 12. The filaments 13, 13 of the bulbs are energized, respectively, from auxiliary coils 15, 15 of the transformer. The

positive terminal of the battery 7' is connected to the filaments 13, 13 through a junction point 14 that is connected also to the common terminal 16 of the coils 15, 15.

The coils 5, 5 and 3, 3 may be separated by means of washers 17 of any suitable non-conducting material. As shown, the auxiliary coils 15 are wound over the primary coils 3 in order to ensure good regulation therein,

55 60 65 In operation, the charging current for the battery 7' divides between the secondary coils 5, 5 and the bulbs 11, 12, as is well understood. That is, during one half cycle, when the terminal 7 is positive, the current flows through bulb 11 to the positive terminal of the battery 7' and thence back to the neutral point 6 of the secondary. In like manner, when the terminal 8 is positive the current flows through bulb 12 to the positive terminal of the battery 7' and thence back to the neutral point 6 of the secondary.

70 75 80 85 90 95 By virtue of the special design of the transformer, namely, the location of the load secondary winding 5 on a portion of the transformer core which is separated from the primary winding 3 by a considerable intervening space and by the non-magnetic spacers 17, a substantial leakage flux is caused to intervene between the primary and load secondary windings. As a well-known concomitant of such a leakage flux between transformer windings, an internal impedance effect is produced whereby the secondary has a phase displacement with respect to the primary, the amount of displacement being dependent upon load current in the secondary. Since the filament-heating current is very nearly in phase with the primary current, it will be seen that the rectified current passing from anode to filament will not reach its maximum or peak value at the same time as the heating current of the filament. In this manner, the filament may be made from a much finer wire than in other designs.

100 There are various ways of obtaining the desired result, with the reactance either internal or external to the transformer, and my invention is not to be construed as being limited to the exact construction shown.

I claim as my invention:—

1. The combination with a transformer comprising a primary winding, a main secondary winding and an auxiliary secondary winding, of a filamentary rectifier bulb having its filament connected to said auxiliary winding and its load circuit connected to said main secondary winding, and means for providing a path for considerably more leakage between said primary winding and said main secondary winding than between said primary winding and said auxiliary winding.
2. The combination with a rectifying device having a heated filament, of a transformer comprising a core having two serially connected magnetizable portions and means for providing a leakage flux between said portions, coils on both of said portions, a supply circuit connected across coils mainly on one of said portions, a filament-energizing circuit connected across coils superposed on said last mentioned coils, and a load circuit including said rectifying device and connected across coils mainly on the other of said portions.
3. The combination with an electrical-discharge device having a heated cathode and an anode, of a transformer comprising a core having two serially related magnetizable portions and means for providing a leakage flux between said portions, coils on both of said portions, a load circuit including said anode and cathode and connected across windings on one of said portions, a filament-energizing circuit connected across windings on the other of said portions, and a supply circuit connected across windings on the latter portion.
4. In combination with an electrical-discharge device having a cathode adapted to be heated and an anode, a supply transformer having a primary winding, a secondary winding closely coupled magnetically with said primary for heating said cathode and another secondary winding substantially less closely coupled magnetically with said primary winding for producing current flow between said anode and cathode.

In testimony whereof, I have hereunto subscribed my name this 27th day of October, 1920.

EDGAR W. BREISCH.
